UNITED STATES PATENT OFFICE.

WILLIAM J. ROA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END ASSEMBLY.

1,199,820.

Specification of Letters Patent.

Patented Oct. 3, 1916.

Application filed July 17, 1915. Serial No. 40,468.

To all whom it may concern:

Be it known that I, WILLIAM J. ROA, residing at 915 Olive street, St. Louis, Missouri, and being a citizen of the United States, have invented certain new and useful Improvements in Car End Assemblies, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an end view illustrating the upper part of a box car equipped with the present invention, Fig. 2 is a plan view of the parts shown in Fig. 1, Fig. 3 is a side elevational view of the parts shown in Figs. 1 and 2, Fig. 4 is a central vertical sectional view, the section being taken on line 4—4 of Fig. 1; Fig. 5 is a sectional view, the section being taken on line 5—5 of Fig. 1, Fig. 6 is a similar view, the section being taken on line 6—6 of Fig. 1, and Fig. 7 is a similar section on line 7—7 of Fig. 1.

The object of the invention is to provide a new type of steel end plate adapted to cooperate with a plurality of steel uprights to form a car end framing which may enter into the construction of new equipment or be adapted with equal facility to reinforce the ends of old box and stock cars.

Another object of the invention is to provide a simple and economical single-sheathed end construction applicable to box and stock cars in which the sides may be of any type. The invention contemplates in the repair of such old cars the elimination at their ends of the old wood construction ordinarily consisting of wood end plates, end posts, braces, belt rails, crip₁ posts and outside sheathing and substituting therefor a steel end frame which is preferably formed of commercially rolled sections united by a single thickness of end lining boards secured to the inner faces of such commercial sections and the whole suitably inclosed and bound together by a pressed end plate of a construction which is especially adapted to inclose

not only the vertical end and corner posts 55 of the car but also to inclose the side plates conveniently connected with such corner posts.

The end plate of the present invention, which end plate is formed preferably of 60 pressed steel, is formed in an angle shaped section deeper at its middle than at its ends and provided at its outer side with a depending apron-like flange and at its top portion with a top flange C, which is narrower at its 65 middle portion than near its ends and is suitably shaped to provide maximum area for connection to longitudinally extending car framing members, the said top flange gradually widening from its middle portion 70 until it reaches a maximum width at the portion of said flange adapted to overlie the side plates of the car. The end plate is preferably formed from a single sheet of metal pressed into proper form in which in 75 the drawings A represents the web portion of said end plate, which web plate is of angular form at its middle portion and comprises the vertical portion 7 and the horizontal portion 8. Depending from the horizontal portion 8 is an apron 9 which is connected by suitable rivets 10 with the end posts 11 and corner posts 12, and it is to be noted that the corner posts 12 are angle shaped in cross section, while the end posts 85 11 and 11^a are Z-shaped in cross section. The sheathing B comprises a series of horizontally disposed planks or boards which are connected by means of bolts or rivets 15 to said end posts and corner posts. The 90 rear flanges 16 of the Z-bars and the flanges 17 of the corner posts lie in approximately the same plane and rest in convenient contact with the outer face of the end sheathing boards while the outstanding flanges 18 95 of the end posts 11 and 11^a stand outwardly from the end sheathing a distance depending upon the width of the web portion 11^b of the Z-bar, this distance in the construction shown being greater in the end posts 100 nearer the center line of the car than at the intermediate end posts between said first mentioned posts and the corner posts.

Connected with the corner posts are angle connection plates 20 which are secured by 105 suitable rivets 21 to the rearwardly extending flanges 12^a of the corner posts and to the horizontal leg 22 of the side plate 23

which, in the present instance, is of angle shape in cross section, its depending leg 24 being spaced outwardly from the flanges 12^a of the corner posts to accommodate side 5 posts and braces (not shown) to which the side sheathing 25 is secured.

The end portions of the end plate are, as shown in the drawings, shaped to envelop the outer end portions of the side plates 23 10 and the top portions of the corner posts 12 and to accommodate this the web A of said end plate terminates at convenient points in proximity to the upper ends of the corner posts 12, so that at its ends said end plate is 15 of substantially angular form in cross section, as best shown in Fig. 7, providing thereby means adapted to closely embrace the upper portions of the corner posts and said outer ends of the side plates.

20 When the parts are assembled the end plate is provided with a bowed portion within the web portion 8 and apron 9, in which a part of said web portion 8 rests vertically above the end posts and said 25 apron extends downwardly parallel with and is connected by direct rivet connection with the outstanding flanges of said end posts, said apron and web portion thence 30 gradually converging toward the outer 35 sides of the car where the web portion 8 merges in said apron portion, as best developed in Figs. 1 and 2. The top flange of the end plate may be bent downwardly at its ends to form a vertical flange 30, 35 which lies parallel with and in close contact with the depending leg 24 of the side plate 23 where said flanges may be connected by suitable rivets 24^a, as shown in Figs. 2 and 3. Thus, the end plate in the construction 40 shown extends beyond the corner posts and incloses the ends of the side plates to which it is secured at the top and sides thereof. Said end plate rigidly connects all the framing members at the ends of the car 45 and insures more equable distribution of the inclosed stresses among said members. The advantages obtained are as favorable as would be those resulting from the use of a pair of Z-bars arranged with their webs at 50 right angles to each other, with the added advantage that the end plate is formed of a single piece of metal which requires no fabrication after it is removed from the press in which it is formed. The end plate 55 may be theoretically divided into two portions in which the Z-shaped portion arranged with its web 7 supports the vertical load imposed and the Z-portion of said plate arranged with its web 8 horizontally resists 60 the stresses resulting from buffing operations and pressure of the lading within the car.

I do not desire to limit myself to the particular arrangement above described, as it 65 is apparent that changes in the form of some

parts of the structure may be made within the scope of the appended claims. For example, rolled shapes of I or L section may be substituted for the Z-shaped end posts shown. In cars having single-sheathed 70 sides and ends, angle corner posts as shown in the drawings, are preferred, but in cars having single-sheathed ends and double-sheathed side walls, Z-shaped corner posts may be more conveniently employed, or they 75 may be of W-section, as desired.

What I claim is:

1. In combination in a car end construction, a plurality of flanged end posts, corner posts and side plates, and a pressed metal 80 end plate extending beyond the corner posts inclosing the ends of the side plates and the upper ends of said end posts and being secured by rivet connection to outstanding flanges of said end and corner posts. 85

2. In combination a plurality of flanged end posts, corner posts having flanges in substantially the same plane, side plates and a bowed end plate extending beyond the side plate and being directly connected to outstanding flanges of said end posts, to flanges of said side plates and corner posts and overlying the upper ends of said corner posts and end posts. 90

3. In combination in a railway car, end 95 posts, corner posts, side plates, and an end plate formed from a single sheet of metal enveloping contiguous end portions of said posts and plates.

4. In combination in a railway car, an end 100 sheathing, end posts connected through flanges thereof to said sheathing, flanged corner posts, side plates connected with said corner posts and an end plate having an angular intermediate portion with a depending apron portion overlapping and being secured to said posts and a top flange overlapping and being secured directly to said side plates. 105

5. In combination in a railway car, an end 110 sheathing, end posts and corner posts connected thereto, an end plate having an angle shaped web with integral top and bottom flanges, said bottom flange resting on the outer side of said end posts and said top 115 flange extending rearwardly overlapping and being adapted for connection with car side plates.

6. A car end comprising, in combination, end and corner posts, sheathing connected 120 to said posts, an end plate having a web of angle shape at its middle portion, said end plate having an inclosing end portion of angle shape comprising the end portions of two flanges which extend across said middle 125 portion.

7. As an article of manufacture, a car end plate formed from a single sheet of metal, said end plate being deeper at its middle than at its ends and at said middle portion 130

comprising an angle shaped web, the end portions of said plate inclosing end portions of side plates and corner posts.

8. As an article of manufacture, a pressed metal car-end-plate comprising a single sheet of metal having an angular web portion wider at its middle portion, both vertically and horizontally, than near its ends and having a vertical apron portion and an inwardly disposed top flange integral with said web portion adapted for direct connection to the side plate of a car.

9. As an article of manufacture, an end

plate for a railway car, said plate comprising a vertical web portion, a horizontal web portion and vertical apron portion, and provided also with vertical flanges and a top flange adapted for connection with car framing members.

In witness whereof I have hereunto set my hand in the presence of two witnesses.

WILLIAM J. ROA.
